UNITED STATES PATENT OFFICE.

JAMES R. POWELL, OF GLASGOW, KENTUCKY, ASSIGNOR OF ONE-HALF TO CHRISTOPHER T. GRINSTEAD, OF GLASGOW, KENTUCKY.

PHOTOGRAPHIC-PRINTING DEVICE.

1,288,609.

Specification of Letters Patent.

Patented June 4, 1918.

Application filed July 12, 1916. Serial No. 108,902.

To all whom it may concern:

Be it known that I, JAMES R. POWELL, a citizen of the United States, residing at Glasgow, in the county of Barren and State of Kentucky, have invented a new and useful Photographic-Printing Device, of which the following is a specification.

The present invention appertains generally to photography, and relates more especially to photographic printing devices.

It is the object of the invention to provide a novel and improved apparatus for producing prints from opaque negatives by a photographic process, whereby the process of producing the prints is cheaper and superior to the ordinary method of printing by means of a transparent negative in back of which the sensitized paper is placed and then exposed to light.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view of the printing device.

Fig. 2 is a longitudinal section thereof.

Fig. 3 is a fragmental side elevation of the device illustrating the use of a mirror or reflector in connection therewith.

In carrying out the invention, there is provided an elongated base 1 adapted to be set upon a table or other support, and in the present instance composed of two alining sections 2 and 3, the base being divided between its ends. The adjacent ends of the sections 2 and 3 are hingedly connected, as at

4, whereby when the device is not in use, the two sections of the base can be folded together, the section 3 swinging under and against the section 2. The sections can be held in folded position by means of a hook 5 or catch 5 carried by the section 3 engage-

able with an eye or keeper 3 carried by the section 2, although any other suitable means can be used for this purpose. If the folding feature of the base is not desired, the base can simply consist of one part. As a means for holding the base unfolded, alining staples or guides 7 are carried by the edges of the sections adjacent the hinge, and a bolt 8 is slidable in said guides whereby when the bolt is slid into engagement with the guides of both sections, said sections will be held in alinement. When the bolt is withdrawn, the sections can be folded. The bolt 8 and catch 5 can be provided at each edge of the base if desired.

Mounted upon the base 1 is an opaque casting or box 9 providing a dark chamber, and composed of telescoping outer and inner sections 10 and 11, respectively. The outer section 10 is secured upon the section 2 of the base, while the section 11 is slidable upon the base, and is provided at that end thereof remote from the section 10 with a lens 12 provided with a suitable shutter (not shown) in the manner of an ordinary camera. The remote end of the section 10 is open and has resting thereagainst a back 13, preferably composed of a frame 13^a having a frosted glass or equivalent panel 13^b therein. The frame 13^a is connected to the section 10 by means of springs 14 which tend to move the back 13 against the end of the section 10. A sensitized-paper holder 15, similar to an ordinary plate holder, is adapted to be inserted downwardly between the section 10 and back 13 to be clamped in place therebetween, the back 13 being yieldable for this purpose.

An angular foot piece 16 is secured to the end of the section 11 and provides an outstanding ear movable upon the base 1 and carrying a thumb screw 17 which can be tightened for holding the section 11 in any adjusted position.

The negative is supported by means of a negative holder comprising a plate or standards 18 carried by a slide 19 movable longitudinally upon the base, and having reflexed edges 20 slidably engaging the edges of the base to guide the slide for longitudinal

movement. A thumb screw 21 is carried by the slide 19 for holding it in various adjusted positions.

In using the device for producing photographic prints, the opaque negative is applied to that side of the holder 18 confronting the lens 12, and is held in place by means of pins, tacks, clips, or the like. The sensitized paper is introduced at the rear 10 end of the casing 9 in front of the back 13, by means of the holder 15 which carries the paper, said holder having a removable slide or shutter 27 normally excluding the light from the sensitized paper and which can be withdrawn after the holder 15 is applied, thereby enabling the sensitized paper to be exposed within the dark chamber. The device is so placed that the negative is subjected to the proper light, whereby the shutter of lens 12 in being opened will result in the printing of the picture, or the like, upon the sensitized paper, which after being properly exposed can be removed and developed. The sensitized paper holder 15 is used in the 25 manner of an ordinary plate holder for cameras, as will be readily understood to those versed in the art. The prints can be made quickly by this photographic process, and do not come in touch with the negative. A number of prints can be made from the 30 same negative without handling the negative, which remains in place upon the holder 18. With the present device, commercial sensitized paper can be used for the production of the negatives, instead of using the sensitized plates or films, and this provides for a saving, both in the cost of the sensitized material and the development of the negatives. The negatives can be applied to 35 the holder 18 even before they are dried, and are not apt to become soiled as are ordinary negatives when handled too frequently or subjected to moisture. The paper negatives can be developed with greater ease, are not 40 sticky as ordinary negatives, and require no chemical such as will stain the hands. Furthermore, with the present negatives there is no running of the emulsion as with ordinary negatives. The paper negatives are 45 also lighter and thinner than ordinary negatives whereby a number of them can be more compactly carried, than with the use of plate or film negatives. "Contrast" sensitized paper can be used for the prints, 50 thereby providing prints of high and artistic quality. Halation is eliminated, which ordinarily results from the reflection and refraction of light by glass plates. Furthermore, the negatives can be "tilted" with 55 the present device, that is, they can be arranged in an oblique plane relative to the axis of the lens 12. Light conditions being the same, the exposure will be of about the same length as when films or glass plates

are used, or a trifle longer, depending on the 65 nature of the sensitized paper. Time is saved, however, in developing and printing the paper negative without drying. The present device provides an admirable one for beginners and amateurs, since the 70 method of printing can be quickly learned and easily carried out. With the opaque paper negatives, recording data can be written upon the back thereof, which will not interfere with the subsequent printing, and 75 the negatives can be readily mailed without being apt to be broken or injured as are plate and film negatives. The present device provides for other advantages which will suggest themselves to those versed in 80 the art.

When the prints are to be of the same size as the negative, the lens 12 is set at a position midway between the holder 15 and the negative holder 18, and by moving the lens 85 12 nearer the holder 15, the prints are reduced, whereas if the lens is moved nearer the negative holder 18, the prints are enlarged. When the holder 15 is removed, the image will be thrown upon the panel or 90 screen 13^b whereby the operator can observe how the picture will look upon the print, in order that adjustments can be made if necessary. Both the negative holder 18 and the casing section 11 can be adjusted, it being 95 preferable to provide the base 1 with graduations 26 for facilitating the adjustment of said parts, although in some cases, the casing 9 can be of a unitary structure as well as the base 1 when the collapsible and adjust- 100 able features are not wanted.

As seen in Fig. 3, a mirror or reflector 22 inclined toward the lens 12 has its lower end seated between the holder 18 and slide 19 and the upper end of the reflector is supported by means of one or more cords or equivalent elements 23 engaged with eyes, pins or similar elements 24 applied to the upper edges of the reflector 22 and holder 18. The negative 25 can therefore be laid 110 upon the base 1 below the mirror or reflector 22, the light rays being reflected between the lens 12 and negatives 25 by means of the reflector 22. This is particularly advantageous when the negative cannot be applied to the holder 18, and permits of a delicate negative being used which would be impossible with the ordinary printing process.

Having thus described the invention, what is claimed as new is:

A photographic printing device comprising a flat base; a casing resting directly on the base; a paper-holder in the rear end of the casing; a lens in the forward end of the casing; a slide mounted to reciprocate on 125 the base in front of the lens; a standard fixed to the slide and defining an angle therewith; a reflector inclined toward the

lens and having its lower edge seated in said angle; and an adjustable connection between the upper edge of the reflector and the standard, that part of the base which 5 lies beneath the reflector and between the slide and the casing forming a negative support.

In testimony that I claim the foregoing as my own, I have hereto affixed my signature in the presence of two witnesses.

JAMES R. POWELL.
